SECTIONAL CURBING

Vance Lines, Pasadena, Calif.

Application May 20, 1935, Serial No. 22,352

8 Claims. (Cl. 94—31)

This invention relates to improvements in concrete curbing.

The general object of the invention is to provide an improved concrete curbing or similar structure pre-cast in sections before it is laid in position.

Another object of the invention is to provide a sectional concrete curbing including novel means for connecting the sections thereof together.

10 A further object of the invention is to provide a sectional concrete curbing including means whereby the sections may be connected either temporarily or permanently.

Other objects and the advantages of this invention will be apparent from the following description taken in connection with the accompanying drawings wherein:

Fig. 1 is a perspective view of a plurality of my improved curbing sections laid in operative relationship with one another to form confining area.

Fig. 2 is an enlarged vertical longitudinal fragmentary section through a plurality of my improved curb sections.

Fig. 3 is an end view of one of the curb sections.

Fig. 4 is a section taken on line 4—4 of Fig. 2.

Fig. 5 is a section taken on line 5—5 of Fig. 2.

Fig. 6 is a section taken on line 6—6 of Fig. 2.

Fig. 7 is a perspective view of the connecting 30 key.

Fig. 8 is an enlarged fragmentary view similar to Fig. 1.

Fig. 9 is a vertical longitudinal section through a plurality of sections of concrete curbing showing a modified form of connecting means.

Fig. 10 is a section taken on line 10—10 of Fig. 9.

Fig. 11 is a section taken on line 11—11 of Fig. 9.

40 Fig. 12 is a vertical longitudinal section through a plurality of concrete curbing sections showing a further modified form of connecting means, and

Fig. 13 is an end view of one of the curbing sections shown in Fig. 12.

Referring to the drawings by reference characters I have indicated a section of my improved concrete curbing generally at 10. As shown each curbing section 10 comprises a body portion 12 which is substantially rectangular in shape and which includes a top wall 13, a bottom wall 14, side walls 15 and 16 and end walls 17. The top and bottom walls are shown as parallel with the end walls 17 and the side wall 15 at approximately

right angles thereto while the side wall 16 is inclined downwardly and outwardly.

Adjacent each end the body 12 has a recess 18 therein which opens through the adjacent end and includes a bottom surface 19, a top surface 20, an end surface 21, and side surfaces 22 and 23. The bottom recess surface 19 is parallel with the bottom wall 14 of the body and the side recess wall 22 is parallel with the side body wall 15 while the side recess wall 23 is inclined parallel with the inclined body wall 16.

The top recess surface 20 is inclined downwardly and inwardly and the end recess surface 21 is inclined upwardly and forwardly to meet the top surface 20. Adjacent each end the body 12 has a transverse aperture 24 therein one end of which opens through the inclined side wall 16 and the opposite end into the adjacent recess 18. Opposite each of the apertures 24 and in line therewith the body has a recess 25 therein which opens into the adjacent end recess 18. (See Figs. 3, 5, and 6.) Intermediate the end recesses 18 the body 12 has a recess 26 therein which opens through the bottom surface 14. Around the bottom edges of the recess 26 the body 12 has an undercut recess 27 therein. Intermediate the ends of the recess 26 the body includes a plurality of spaced integral rib members 28 which at their lower ends terminate flush with the bottom edge of the recess 26.

Positioned in the undercut recess 27 I provide a concrete closure slab 29 which is secured to the body 12 by cementing it thereto as indicated at 30. When the closure slab 29 is placed in position a quantity of cement may be placed on the upper face thereof adjacent the locality of the ribs 28 to cement the lower ends of the ribs to the closure slab as indicated at 31 in Fig. 2. Although I have shown and described the body 12 as being hollow it will be understood that it may be made solid.

For connecting two sections 10 of my improved curbing I provide a key member which is indicated generally at 32 and shown in detail in Fig. 7. As shown the key member 32 includes a body portion 33 which is made of concrete and includes a bottom surface 34, a top surface 35, end surfaces 36 and side surfaces 37 and 38. The bottom surface 34 and the side surface 37 are approximately at right angles to each other while the side surface 38 is inclined upwardly and inwardly and the end surfaces 36 are each inclined upwardly and inwardly.

From a point 39 intermediate the ends 36 the

top surface is inclined downwardly towards each end 36 as indicated at 40.

In the sides 37 and 38 of the body 33 adjacent each top corner thereof the body 33 has a recess 41 therein which opens through the top surface and the adjacent end surface. In the sides 37 and 38 the body further includes adjacent each bottom corner thereof a recess 42 which opens through the bottom surface and the adjacent end surface.

Within the confines of each of the top recesses 41 the body has a transverse aperture 43 therein. In each side of the body 33 adjacent each end thereof the body has a secured groove 44 therein each of which at one end opens into a top recess 41 and at the opposite end opens into a bottom recess 42.

From the foregoing it will be seen that the general shape of the key member 32 at each side of the point 39 corresponds to the shape of the end recess 18 of a curbing section 10.

When connecting two of the curbing sections 10 a key member 32 is positioned in one of the end recesses 18 of the curb and when so positioned the point 39 of the key is flush with the adjacent end surface of the curb thereby leaving half of the key member projecting beyond the adjacent end of the curb. Thereafter another curb section is laid with one end 17 facing the key member 32 and moved towards the key member until the projecting portion of the key member is positioned in the adjacent end recess 18 of the record block as clearly shown in Fig. 2 thus forming a connecting joint 45.

When the curbing sections 10 are laid for temporary use a metal pin 46 is positioned in the aperture 24 of the curbing and extends through the key aperture 43 into the recess 25 of the curb as clearly shown in Fig. 5.

When two sections of curbing are thus connected the key member 32 prevents relative transverse and vertical movement of the curb sections and the pins 46 prevent relative lateral movement of the curb sections.

When the curbing is laid for permanent installation the pins 46 are omitted and cement forced by a cement gun, into the curb apertures 24. This cement is forced through each of the apertures 24, through the key apertures 43 and into the curb recess 25 thus forming a cement plug member 47. At the same time cement fills the key recesses 41 and passes down the key grooves 44 into the key recesses 42. Thus it will be seen that when the cement hardens the key member is firmly cemented to each of the curb sections with which it is associated and that the cement plug 47 prevents relative lateral movement of the curb sections. In use the curbing sections are preferably imbedded in the ground as shown in Fig. 5.

In Figs. 1 and 8 I have shown my improved curbing assembled for use and have shown various other forms as well as the straight sections 10, into which my improved curbing may be made. At 48 I have shown a corner section of curbing and at 49 I have shown a section of curbing in the form of a cross while at 50 I have shown a section of curbing in the form of a T. At 51 I have shown curbing formed semi-circular as at 52 and it is formed into quadrants.

The sections 48, 49, 50, 51 and 52 are all formed with recesses 18 in which key members 32 may be positioned to form a connecting joint 45. At 53 I have shown a straight section of curbing similar

to the curbing 10 which intermediate its length has a recess 18a therein which opens through one side of the curbing to receive a key member 32 to form a joint 45. From the foregoing it will be seen that my improved sectional curbing may be made in any form desired.

In Figs. 9, 10 and 11 I have indicated a modified form of curbing section generally at 55. As shown each curbing section 55 comprises a body portion 56 which is substantially rectangular in shape and which includes a top surface 57, a bottom surface 58, side surfaces 59 and 60, and end surfaces 61. The top and bottom surfaces are shown as parallel with the end surfaces at right angles thereto while the side surface 60 is inclined downwardly and outwardly. Adjacent each end the body 56 has a recess 62 therein which opens through the adjacent end and through the side surface 60 thereof and includes a side surface 63, an end surface 64, a top surface 65 and a bottom surface 66. The end surface 64 of the recess is shown as substantially parallel with the end surface of the body while the top recess surface is inclined downwardly and outwardly and the bottom surface is inclined upwardly and outwardly. Adjacent each end the body 56 has a vertical aperture 67 therein one end of which opens through the top surface 57 thereof and the opposite end opens into the adjacent end recess 62. Opposite each of the apertures 67 and in line therewith the body has a recess 68 therein which opens into the adjacent end recess 62. Intermediate the end recesses 62 the body 56 has a recess 69 therein which opens through the bottom surface 58. Around the bottom edges of the recess 69 the body 56 has an undercut recess 70 therein. Intermediate the ends of the recess 69 the body includes a plurality of spaced rib members 71 which at their lower ends terminate flush with the bottom edge of the recess 69.

Positioned in the undercut recess 70 I provide a concrete closure slab 72 which is secured to the body 56 by cementing it thereto as at 73. When the closure slab 72 is placed in position a quantity of cement may be placed on the upper face thereof adjacent the locality of the ribs 71 to cement the lower ends of the ribs to the closure slab as indicated at 74 in Fig. 9.

For connecting two of the curb sections 55 I provide a key member 75 which includes a body portion 76 made of concrete and having a bottom surface 78, a top surface 79, end surfaces 80 and side surfaces 81 and 82. The end surfaces 80 are at approximately right angles to the side surface 81 while the side surface 82 is inclined downward and outward. From a point 83 intermediate the length of the body the top surface 79 is inclined upwardly and outwardly and from a point 84 intermediate the length of the body the bottom surface 78 is inclined downwardly and outwardly.

In the side 81 of the key body 76 adjacent each top corner thereof the body 76 has a recess 85 therein which opens through the top surface 79 and the adjacent end surface. The side 81 further includes adjacent each bottom corner thereof a recess 86 which opens through the bottom surface and the adjacent end surface. Intermediate the length of each top recess 85 the top surface 79 has a transverse recessed groove 87 therein one end of each of which opens into its associated recess 85 and the opposite end of which terminates at a position spaced from the side surface 82. (See Figs. 10 and 11.) Inter-

mediate the length of each bottom recess 86 the bottom surface 78 has a transverse recessed groove 88 therein one end of each of which opens into its associated recess 86 and the opposite end terminates at a position spaced from the side surface 82.

Intermediate the length of the grooves 87 and 88 the key body 76 has an aperture 89 therethrough one end of each of which opens through the top surface 79 and the opposite end through the bottom surface 78.

From the foregoing it will be seen that the general shape of the key member 75 at each side of the points 83 and 84 corresponds to the shape 15 of the end recesses 62 of a curbing section 55.

When connecting two of the curbing sections 55 they are positioned with adjacent ends abutting and with adjacent recesses 62 in alignment. A key member 75 is inserted into the end recesses 62 of the curb sections from the sides 82 thereof and when so positioned the points 83 and 84 of the key are flush with the adjacent end surfaces 61 of the curb thereby leaving half of the key projecting in one of the curb sections 25 and the other half in the other curb section.

From the foregoing it will be seen that the key member prevents relative vertical and lateral movement of two connected curb sections.

When the curbing sections are laid for temporary use metal pins 90 are positioned in the apertures 67 of the curbing sections and extend through the key apertures 89 into curb recesses 68 as clearly shown in Figs. 9 and 10. The pins 90 prevent relative transverse movement between 35 adjoining curbing sections.

When the curbing is laid for permanent installation the pins 90 are omitted and cement forced by a cement gun, into the curb apertures 67. This cement is forced through each of the 40 curb apertures 67, through the key apertures 89 and into the curb recess 68 thus forming a cement plug 91. At the same time cement fills the key recesses 85 and 86 thus when the cement hardens the key member is firmly secured to the 45 curb sections with which it is associated.

In Figs. 12 and 13 I have indicated a further modified form of curbing section generally at 95. As shown each curbing section 95 comprises a body portion 96 which is substantially rectangular in shape and includes a top surface 97, a bottom surface 98, side surfaces 99 and 100, and end surfaces 102 and 102'. The top and bottom surfaces are shown as parallel with the end surfaces at right angles thereto while the side surfaces 55 face 100 is inclined downward and outwardly. Intermediate the ends 61 of the curbing section 95, the body 96 has a recess 103 therein which opens through the bottom surface 98 thereof. Around the bottom edges of the recess 103 the body has an undercut recess 104 therein. Intermediate the ends of the recess 103 the body 60 includes a plurality of spaced integral rib members 104 which at their lower ends terminate flush with the bottom edge of the recess 103.

Positioned in the undercut recess 104 I provide a concrete closure slab 105 which is secured to the body 96 by cementing it thereto as indicated at 65 106. When the closure slab 105 is placed in position a quantity of cement may be placed on the upper surface thereof adjacent the location of the ribs 104 to cement the lower ends of the ribs to the slab 105 as indicated at 107 in Fig. 12. At the end 102 the body 96 has a plurality of dowel receiving recesses 108 therein which open through 70 75 the end surface 102 and are shown as three in

number, one being positioned adjacent the top of the body and two adjacent the bottom thereof. At the end 102' the body has a plurality of dowel pin members 109 embedded therein with portions of the dowels extending beyond the end surface 5 102'. The dowel pins 109 are shown as three in number and are positioned to correspond to the positions of the previously described dowel receiving recesses 108. (See Fig. 13.)

Embedded in the curbing body 96 adjacent each 10 of its ends I provide a pair of superimposed transverse pin members 110 each of which at each side of the body extends beyond the adjacent surface thereof and includes an enlarged head portion 112 spaced from the adjacent side of the curb body. 15 Mounted on each pin of a pair of the pins 110 at one end of the curb body I provide a securing member 113 which is shown as a length of malleable iron wire wound around the pin 110 and bent around itself as at 114. Each of the securing 20 members extends outward beyond the adjacent curb end a predetermined distance.

With the curb sections 95 a joint member 115 is preferably used. The joint member 115 may be made of presswood, bako wood or other suitable 25 material and has dowel apertures 116 therein which correspond in positioning to the positioning of the dowels 109.

When the curbing sections 95 are laid they are placed with the end 102 of one curb section facing the end 102' of the next adjacent curb section and a joint member 115 is positioned on the dowels 109 and then the dowels are positioned in the dowel recesses of the adjacent curb section and the two curbing sections moved together until the 30 adjacent end faces thereof firmly engage the joint member 115 as clearly shown at the "A" location in Fig. 12. When the curbing sections are thus brought together the operator ascertains that the fastening members 113 of the one section overlie their associated pin members 110 of the adjacent section as shown at the "A" location. Thereafter the operator bends the free ends of the securing members 113 down and around their 40 associated pin members 110 as shown at the "B" 45 location thereby securely connecting the two adjacent curb sections together.

The securing members 113 prevent relative lateral movement between two adjoining curb sections and the dowel pins 108 prevent relative vertical and transverse movement between the curb sections. 50

From the foregoing description it will be apparent that I have provided a novel sectional concrete curbing which is simple in construction and 55 highly efficient in use.

Having thus described my invention, I claim:

1. A curbing comprising a plurality of separate sections, each of said curb sections being made of concrete and including a top, bottom, sides and 60 ends, each of said curb sections having a recess adjacent each end thereof, each of said recesses including a bottom surface, a top surface, side surfaces, and an end surface, said recess end surfaces being inclined upwardly and outwardly and said recess top surface being inclined inward and downward, there being a transverse aperture in each of said curb sections opening into each of said end recesses, said curb sections being positioned end to end with said end recesses thereof 65 communicating to form a chamber, and a key member in each of said chambers, each of said key members including a portion thereof positioned in the end recess of one curb section and another portion thereof positioned in the end 70 75

recess of the adjacent curb section, said key member portions being shaped to match the shape of said end recesses.

2. A curbing comprising a plurality of separate sections, each of said curb sections being made of concrete and including a top, sides and ends, each of said curb sections having a recess adjacent each end thereof, each of said recesses including a bottom surface, a top surface, side surfaces, and an end surface, said recess end surface being inclined upwardly and outwardly and said recess top surface being inclined inward and downward, there being a transverse aperture in each of said curb sections opening into each of said end recesses, said curb sections being positioned end to end with said end recesses thereof communicating to form a chamber, and a key member in each of said chambers, each of said key members including a portion thereof positioned in the end recess of one curb section and another portion thereof positioned in the end recess of the adjacent curb section, said key member portions being shaped to match the shape of said end recesses, adjacent each top corner of each side of said key member, said key member having a recess therein opening through the top surface and the side surface thereof, said key member having a recess adjacent each bottom corner of each side opening through the bottom surface and the side surface thereof, said corner recesses of said key member being confined within said end recesses forming said chamber, said key members having recesses in the sides connecting each pair of said top and bottom, each of said portions of said key members having an aperture, each of said key apertures being positioned within the confines of one of said corner recesses and said key apertures approximately aligning with said curb section apertures, said curb section apertures, 40 said key apertures, and said key recesses being filled with cement.

3. A curbing comprising a plurality of separate sections, each of said curb sections being made of concrete and including a top surface, a bottom surface, opposed side surfaces, and end surfaces, said top and bottom surfaces being approximately at right angles to said end surfaces and one of said side surfaces being approximately at right angles to said top and bottom surfaces, the other 50 of said side surfaces being inclined downward and outward from said top surface, each of said curb sections having a recess adjacent each end thereof opening through said end surfaces, each of said recesses including a bottom surface substantially parallel with the bottom surface of its associated curb sections, an end surface, a top surface, and side surfaces, the one of said recess side surfaces adjacent said inclined curb surface being approximately parallel therewith and the 60 other of said recess side surfaces being approximately parallel with the opposite side surface of said curb section, said recess end surface being inclined upward and outwardly and said recess top surface being inclined inward and downward, there being a transverse aperture in each of said curb sections opening into each of said end recesses, each of said curb sections having a recess opening through the bottom surface thereof intermediate said end recesses, a concrete slab positioned in each of said intermediate recess to close the bottom thereof, said concrete slabs being cemented to their associated curb sections, a plurality of transverse ribs in each of said intermediate recesses integral with said curb sections and extending downward to their associat-

ed slabs, said curb sections being positioned end to end with said end recesses thereof communicating to form a chamber, and a key member in each of said chambers.

4. A curbing section made of concrete and including a top, sides and ends, said curb section end having a recess therein, said recess including a bottom surface, a top surface, side surfaces, and an end surface, said recess end surface being inclined upwardly and said recess top surface being inclined upwardly and at an angle to said recess end surface, and a key member in said recess, said key member being shaped to match the shape of said end recess, said key member at each end and at each side having a recess therein extending through the top surface, said key member having other recesses opening through the bottom surface thereof, said recesses of said key member being confined within said end recess of said section, said key member having a recess in the sides connecting each pair of said top and bottom recesses, said key recesses being filled with cement.

5. A curbing comprising a plurality of separate sections, each of said curb sections being made of concrete and including a top, sides and ends, each of said curb sections having a recess adjacent each end thereof, each of said recesses including a bottom surface, a top surface, side surfaces, and an end surface, said curb sections being positioned end to end with said end recesses thereof communicating to form a chamber, a key member in each of said chambers, each of said key members including a portion thereof positioned in the end recess of one curb section and another portion thereof positioned in the end recess of the adjacent curb section, said key members at each end and at each side having a recess therein extending through the top surface, said key member having other recesses opening through the bottom surface thereof, said recesses of said key member being confined within said end recesses forming said chamber, said key members having recesses in the sides connecting each pair of said top and bottom recesses, each of said key apertures being positioned within the confines of said first mentioned key recesses, said curb section apertures, and said key recesses being filled with cement.

6. A curbing comprising a plurality of separate sections, each of said curb sections being made of concrete and including a top, sides and ends, each of said curb sections having a recess adjacent each end thereof, each of said recesses including a bottom surface, a top surface, side surfaces, and an end surface, said recess top surface being inclined upwardly, said curb sections being positioned end to end with said end recesses thereof communicating to form a chamber, a key member in each chamber, each of said key members including a portion thereof positioned in the end recess of one curb section and another portion thereof positioned in the end recess of the adjacent curb section, said key member portions being shaped to match the shape of said end recesses, said key members at each end and at each side having a recess therein extending through the top surface, said key member having other recesses opening through the bottom surface thereof, said recesses of said key member being confined within said end recesses forming said chamber, said key members having recesses in the sides connecting each pair of said top and bottom recesses, each of said key apertures being positioned within the confines of said key recesses.

of said first mentioned key recesses, said curb section apertures, and said key recesses being filled with cement.

7. A curbing comprising a plurality of separate sections, each of said curb sections being made of concrete and including a top, sides and ends, each of said curb sections having a recess adjacent each end thereof, each of said recesses including a bottom surface, a top surface, side surfaces, and an end surface, said recess end surface being inclined upwardly and said recess top surface being inclined upwardly and at an angle to said recess end surface, there being transverse apertures in each of said curb sections opening into each of said end recesses, said curb sections being positioned end to end with said end recesses thereof communicating to form a chamber, a key member in each chamber, each of said key members including a portion thereof positioned in the end recess of one curb section and another portion thereof positioned in the end recess of the adjacent curb section, said key member portions being shaped to match the shape of said end recesses, said key members at each end and at each side having a recess therein extending through the top surface, said key member having other recesses opening through the bottom surface thereof, said recesses of said key member being confined within said end recesses forming said chamber, said key members

having recesses in the sides connecting each pair of said top and bottom recesses, each of said portions of said key members having an aperture, each of said key apertures being positioned within the confines of said first mentioned key recesses and said key apertures approximately aligning with said curb section apertures, said curb section apertures, said key apertures, and said key recesses being filled with cement.

8. A curbing comprising a plurality of separate sections, each of said curb sections being made of concrete and including a top, bottom, sides and ends, each of said curb sections having a recess adjacent each end thereof, each of said recesses including a bottom surface, a top surface, side surfaces, and an end surface, said recess top surface being inclined inwardly and downwardly, said curb sections being positioned end to end with said end recesses thereof communicating to form a chamber, and a key member in each of said chambers, each of said key members including a portion thereof positioned in the end recess of one curb section and another portion thereof positioned in the end recess of the adjacent curb section, said key member portions having their top surfaces inclined inwardly and downwardly to match the shape of the top surfaces of said end recesses and means to hold said key members in place.

VANCE LINES. 30
